UNITED STATES PATENT OFFICE

1,984,089

TELEPHONE LOCK

Samuel Segal, New York, N. Y.

Application April 22, 1932, Serial No. 606,896

11 Claims. (Cl. 179—189)

The present invention has general reference to a locking device more particularly adapted to reduce the range of selections on the impulse transmitting rotary ring of a dial telephone, 5 the locking device being adapted to be inserted and locked in any one of the several finger openings of the rotary ring to prevent unauthorized use of the telephone for outgoing calls.

It is an object of the invention to provide a locking device which may be quickly attached to the dial of an automatic telephone to render the dial ineffective for practical purposes.

It is a particular object of the invention to provide a locking device for an automatic dial telephone comprising pivotally disposed means having shiftable terminals adapted to be pressed through a finger opening of the dial ring and subsequently cooperate therewith to prevent the device from being removed from the dial ring.

It is a further object of the invention to provide a locking construction of the character referred to which may be unlocked from the telephone dial by the aid of a manually actuated key for operating separate means to free the shiftable means from the adjacent walls of a finger opening.

It is still a further object to provide a lock for a dial telephone, which comprises few parts, 30 which is easy to assemble, which is reliable in operation and which may be economically manufactured.

Other objects are in part obvious and in part pointed out hereinafter.

The invention accordingly comprises the features of construction, combination of elements and arrangements of parts which will be exemplified in the construction hereinafter set forth and the scope of the application thereof 40 will be indicated in the appended claims.

For clear understanding of the invention attention is directed to the embodiment shown in the accompanying drawing in which:

Fig. 1 is a sectional view taken across the 45 vertical post of an automatic telephone showing the rotary dial in perspective, and in which the locking device according to the invention is mounted.

Fig. 2 is a fragmentary view of the base of the 50 telephone showing in elevation the locking device attached to the rotary dial which is also illustrated partly in section and taken along the line 2—2 of Fig. 1.

Fig. 3 is a view taken on the line 3—3 of 55 Fig. 4.

Fig. 4 is a view taken along the line 4—4 of Fig. 3.

Fig. 5 is a view taken approximately on the line 5—5 of Fig. 3.

Fig. 6 is a plan view of the plug with the 5 jacket and barrel removed and

Fig. 7 is a plan view of the barrel and

Fig. 8 is an elevation view of the barrel.

Referring to the drawing, the base of a telephone instrument is designated 10 and on this 10 base is rotatably mounted in the usual fashion a ring 11 of an impulse transmitting dial device. This ring is provided with plurality of openings 15 as 12 in which a finger of the operator may be inserted for selectively displacing the ring a predetermined distance in the direction of the arrow and toward the fixed stop 13 for electrically recording a predetermined order of signals or impulses to obtain a called station.

According to the invention, provision has been 20 made to prevent unauthorized use of the telephone for outgoing calls however without disturbing the operation of the telephone as to reception of incoming calls. To this end, a lock 25 device generally indicated 15 is mounted on the ring and arranged in one of the openings thereof in order to cut down the range of selections of both letters and numbers of an indicia carrying card usually forming a background for the 30 rotary ring.

As shown in Fig. 1 the locking device 15 is disposed in the first opening of the rotary ring with respect to the stop 13 in a counter clockwise direction although in actual practice the locking device may be inserted in any of the 35 other openings of the dial ring 11 to cut down the range of character selections and render the dial ineffective for practical purposes.

The locking device is in the form of a plug or body having an upper cylindrical part 16 from 40 which integrally depends a reduced cylindrical portion 17. The plug is provided with a bore 18 disposed eccentrically with respect to the vertical axis of the plug, which bore terminates a slight distance above the bottom face 19 of the 45 depending portion 17.

The upper part of the plug is provided with an irregular or approximately heart shaped recess 20 in which a cam comprising wings 21 and 22 carried by the cylindrical barrel 23 is 50 seated. The barrel 23 is loosely and rotatably mounted in the bore 18 of the plug and is provided with a key receiving slot 24 coextensive with the height thereof. This slot is in registration 55 with a slot 25 formed between the wings 21 and

22, the latter being integral with the barrel or suitably carried in unison thereby.

In the normal position of the cam, its wing 21 is disposed intermediate the curved side 26 of the reentrant lug 27 and the upper portion 29 of the pivoted latch member or arm 30 and its opposite wing 22 is arranged between the upper curved rim 31 of the plug and the upper portion 32 of the pivoted latch arm 33.

10 The plug is provided with opposed and spaced slots 34 which extend substantially coextensive the height thereof and communicate with the upper heart shaped recess 20 and in each of these slots a latch member as 30, already alluded to is pivotally mounted on a fulcrum pin 35 secured to the sides of a respective slot, the upper portions as 29 of a latch arm being so arranged as to extend into the recess 20.

Each of the latch arms which are identical 20 in construction as to size and shape is provided with a lower lip portion generally designated 36, which portion includes a laterally extending shoulder 37 and a downward and inwardly inclined face 38.

25 The lip portions of the latch arms are normally urged by the helicoidal spring 39 beyond their respective slots as to overhang the sides of the reduced portion 17 of the plug, which spring has its free portions abutting an inner face of an adjacent latch arm to urge the same outwardly, the spring being also disposed in a suitable opening 40 passing through the reduced portion 17 of the plug. Thus the lower portions of the latch arms by reason of the action of spring 39 extend beyond the sides of the reduced portion of the plug (see Fig. 5) while their upper portions normally are urged in a direction towards each other and are disposed (see Fig. 3) within close proximity of a side of an adjacent wing of the cam.

40 The upper part of the plug is provided with several spaced and superposed openings as 41 and although only two of these openings are illustrated in the form according to Fig. 4, it is within the province of the invention to provide more than two when desired. These openings extend radially of the plug and communicate with corresponding openings as 42 of the barrel 23.

50 Suitably mounted in an opening 41 of the plug and the extension thereof as 42 in the barrel are tumblers 43 and 44. As shown only two tumblers are disposed in an opening 41 and its extension but in practice more than two may be utilized when so required.

55 Interposed between the depending wall 45 of a jacket 46 and the tumblers as 43 are the helicoidal springs 47 each of which being disposed in an opening 41.

60 With the key removed from the slot 24 of the barrel, the adjacent tumblers of the several rows are normally urged, say to the right (see Fig. 4). The extreme position of the several tumblers 44, if the key 48 be removed from the barrel are shown by the dotted lines in Fig. 4. In such position the several tumblers 43 would be extended into an aligned opening 42 and consequently prevent the barrel from being rotatably displaced about its own vertical axis.

70 If the key 48 be inserted in slot 24 the bitings as 49 thereof operate to displace the tumblers 44 a predetermined distance against companion tumblers 43 and in a direction towards and against the action of an associated spring 47, 75 such that faces as 50 and 51 of contiguous tum-

blers of the several rows of tumblers line up. The lengths of the several tumblers 44 are so fashioned to cooperate with the bitings 49 of the key to cause the meeting faces 50 and 51 of the several sets of tumblers to line up. If the meeting faces of the tumblers be lined up, which positions are illustrated in Fig. 4, the barrel 23 may be rotated by returning the key 48.

Upon displacement of the barrel, the wings 21 and 22 of its cam will cause the upper portions 10 29 and 32 of the latch arms to move outwardly which action will also cause the lower lip portion of the arms to move inwardly within the limits of the reduced part 17 of the plug and against the resistance of spring 39, the latch arms when 15 swung on their pivots being guided in a respective slot 34.

Any key will not operate to displace the tumblers 44 as to have the meeting faces 50 and 51 of contiguous tumblers line up and consequently 20 permit the rotation of the barrel. The bitings of a key must be so cut as to displace the tumblers a certain distance in order that the aforementioned meeting faces of the several rows of tumblers line up. In actual practice various 25 combinations of lengths for the bitings as 44 may be used and a key as 48 may be fashioned accordingly to line up the meeting faces of the tumblers and it is to be understood that the invention is not limited to two sets of tumblers 30 or to a key with just two bitings.

A jacket or casing is attached to the expanded part 16 of the plug. This jacket comprises a top wall 53 from which integrally depends the annular flange 45 and the latter is frictionally secured to said part 16, the top wall 53 together with the flange 45 constitute an inverted cup in which the upper expanded part of the plug is received, the upper wall having an opening 54 in which the upper portion of the barrel is journaled.

The lower rim 56 of flange 45 may be slightly bent inwardly to overlap the lower circumferential edge of the expanded part of the plug to supplement the friction between the jacket and 45 the plug for positively preventing the jacket from being disengaged therefrom.

Associated with the annular flange 45 is a depending extension 57. This extension overhangs a part of the restricted portion of the plug and 50 its purposes is to cooperate with the outer face of the dial ring 12 to prevent rotation of the locking device about its vertical axis when the device is locked to a finger opening of the dial ring and when it is desired to release the locking device from the dial ring.

In Fig. 1, the locking device is attached to the dial ring in one of the finger openings. If it is desired to remove the locking device, a key as 48 having proper bitings is placed into the slot 60 of the barrel. This action causes the meeting faces of adjacent tumblers in the several rows to line up. The key is now turned, causing cam wings 21 and 22 to move outwardly and move in turn the upper portions 29 and 32 of the latch arms, such that their lower lip portions 36 move inwardly and within their slots 34, thereby offering no resistance to the withdrawal of the reduced part 17 of the locking device from an opening as 12 of the dial ring.

70 When the locking device is withdrawn from a finger opening, lip 36 of the latch arms automatically move outwardly as to extend beyond the reduced part 17 of the locking device, and the inner portions of these arms move inwardly, 75

one of which shifts cam wing 21 against the abutment side 26 of the reentrant lug 27 which in this instance serves as a stop.

Where it is desired to attach the locking device 5 in one of the finger openings of the dial, the lower reduced portion thereof is placed into a finger opening and the device is slightly pressed downwardly. The sides of the finger opening meets the inclined faces 38 of the latch arms, 10 which operation causes the lips 36 of these arms to be forced against the action of the spring 39 to a position within their respective slots 34. In this way the part of reduced portion of the locking device which carries the lip members 15 of the latch arm may be brought below the elevation of the surrounding walls of a finger opening. Once free of the sides of a finger opening, the lips of the latch arms again expand outwardly as to come under the lower face of 20 the dial ring which is now locked between the upper faces of these lips and lower face or shoulder 57 of the expanded part 18 of the plug (see Fig. 2), the lips 36 when disposed below the dial ring and expanded prevent the 25 locking device to be removed from the dial ring and the shoulder 57 is sustained and seated on the dial ring adjacent a plug receiving finger opening.

As illustrated the locking device is provided 30 with several sets of tumblers of the cylindrical type or the like for cooperating with a properly cut key to line up the meeting faces of contiguous tumblers of a row to permit subsequent turning of the barrel. Of course, other forms of 35 tumblers may be employed for a similar purpose such as the laminated form of tumblers or their equivalents within the province of the invention and any appropriate type of key may be utilized to line up the tumblers in the several rows 40 preparatory to displacing the barrel.

In the broader aspects of the invention, I do not desire to be understood as limiting its embodiments to details herein shown illustratively 45 within the scope of the appended claims without departing from the spirit of the invention.

I claim:

1. In a device for reducing the range of selections of a perforated dial of a telephone, the 50 combination of a member having complementary portions, one constituting an expanded part, and another a reduced part, the parts being integrally connected, the expanded part having a shoulder adapted to seat on the dial about a 55 perforation, the reduced portion being disposed in said perforation and having shiftable means extending beyond the limits thereof, the shiftable means being displaceable upon engagement with the walls of said perforation towards the 60 interior of the member, and subsequently diverging outwardly as to extend beyond the walls of a perforation to prevent the disengagement of the member from the dial and key operative means for bringing said shiftable means towards 65 the member preparatory to its removal from a perforation and means bodily movable with said member and disposed adjacent the peripheral edge of said dial and overhanging the latter to prevent rotation of said member about its 70 vertical axis.

2. In a device for reducing the range of selections of a telephone dial, the combination of, a member having an expanded part and a reduced part, the expanded part being sustained by the 75 dial about a perforation and the reduced part

being adapted to pass through the perforation, shiftable means extending from the reduced part and projecting beyond the limits thereof and adapted to be displaced therewith upon engagement with the walls of said perforation, means for extending the shiftable means beyond the limits of the reduced part after having left the walls of the perforation to prevent disengagement of the member therefrom, key operative means for bringing said shiftable means 10 within the limits of the reduced part preparatory to the removal of the member from the perforation, and overhanging means disposed adjacent the outer peripheral edge of the dial to prevent rotation of said member upon operation of said 15 key operative means.

3. In a device of the character described for cutting down the range of selections of a telephone dial, the combination of a member having an opening, a key receiving barrel disposed 20 therein, the member having a recess, a cam having wings carried by the barrel and extending laterally thereof but disposed within said recess, latch means pivotally connected to opposed portions of said member, upper portions 25 of the latch means projecting into said recess and within close proximity to the wings of the cam, spring means for holding the lower portion of the latch means normally beyond the limits of a part of the member, and means to permit 30 rotation of said barrel for operating said cam to dispose the lower portions of the latch means within said part and means movable with said member and disposed adjacent the peripheral edge of said dial to prevent rotation of said 35 member relative to said dial.

4. In a device of the character described, the combination of, a member having an opening, a key receiving barrel disposed therein, the member having a recess, a lug extending within the 40 recess and at one side of said opening, a cam having wings carried by the barrel and extending laterally thereof but disposed within the recess, the lug constituting a stop for one of the wings, pivotal latch means having portions 45 within the recess adapted to be actuated by said wings, the pivotal latch means including other parts normally extending beyond the limits of said member and means for rotating the barrel to drive said parts within the member. 50

5. In a lock device adapted to be inserted in a finger pull opening of a dial for reducing the range of character selections thereof, the combination of, a member, a key receiving barrel disposed therein, cam means carried by the barrel, latch means pivoted to said member, means for holding corresponding portions of the latch means beyond a restricted part of the member, a plurality of sets of tumblers disposed within the device, spring means for normally urging several of said tumblers to prevent rotation of the barrel, a jacket secured to a part of the member and forming an abutment for said spring means, and key means insertable in said barrel for arranging several of the tumblers 60 in a predetermined order for moving the aforementioned portions within the restricted part of the member and means bodily movable with said member overhanging said restricted part 65 and cooperating with the rim of said dial to prevent rotation of said member relative to said dial. 70

6. A lock device adapted to be inserted in a finger pull opening of a dial for reducing the range of character selections thereof; the com- 75

bination of, a member, a key receiving barrel disposed therein, cam means carried by the barrel, latch means pivoted to said member, means for holding corresponding portions of the latch 5 means beyond a part of the member, tumbler means within the member, spring means for normally urging the tumbler means to prevent rotation of the barrel, a jacket secured to said member to prevent displacement of the tumbler 10 and spring means, the aforementioned corresponding portions of the latch means being adapted to be moved by the sides of a finger pull opening towards and within the member when a portion thereof is passed through said 15 opening and means bodily movable with said member and overhanging a portion of said dial and cooperating therewith to prevent rotation of said member in respect to said dial.

7. A lock device adapted to be inserted in a 20 finger pull opening of a dial for reducing the range of character selections thereof, the combination of, a member having an opening, a key receiving barrel disposed therein, cam means carried by the barrel, latch means pivoted to 25 said member, means for holding corresponding portions of the latch means beyond a part of the member, tumbler means within the member, spring means for normally urging the tumbler means to prevent rotation of the barrel, a jacket 30 secured to said member to prevent the displacement of the tumbler and spring means, the aforementioned corresponding portions of the latch means being adapted to be moved by the sides of a finger pull opening toward the sides 35 of the member and the jacket having means overhanging the rim of said dial and cooperating therewith to prevent rotation of said device relative to said dial.

8. In a device for reducing the range of selections of a perforated dial of a telephone, the 40 combination of, a member having complementary portions, one constituting an expanded part, and another a reduced part, the parts being integrally connected and forming a shoulder 45 adapted to seat on the dial about a perforation, the reduced portion being disposed in and below said perforation, means bodily movable with said member and cooperating with the rim of said dial and spaced from said reduced part 50 to prevent rotation of said member in said per-

foration and means to prevent removal of the aforementioned restricted part from said perforation.

9. In a device for reducing the range of selections of a perforated dial of a telephone, the 5 combination of, a member having complementary portions, one constituting an expanded part and another a reduced part, the parts being integral- 10 ly connected and forming a shoulder adapted to seat on the dial about a perforation, the reduced portion being disposed in and below said perforation, a jacket secured to said expanded part, key operative means carried by said member to permit or prevent removal of said restricted part from said perforation and a lug associated with 15 said member and overhanging said dial to prevent the rotation of said restricted part in said perforation.

10. In a device for reducing the range of selections of a perforated dial of a telephone, the 20 combination of, a member having expanded and reduced parts forming a shoulder adapted to seat on said dial about a perforation, the reduced portion being removably disposed in and below said perforation, a jacket secured to said ex- 25 panded part, key operative means carried by said member to permit or prevent removal of said reduced part from said perforation and means overhanging said reduced part and disposed adjacent to the outer rim of said dial and cooper- 30 ating therewith and bodily movable with said member to prevent rotation of said member relative to said dial.

11. In a device for reducing the range of selections of a perforated rotatable dial of a tele- 35 phone, the combination of, a member having ex- panded and reduced parts forming a shoulder adapted to seat about a perforation of said dial, the reduced portion being removably disposed in and below said perforation and occupying 40 substantially the entire area thereof, a jacket secured to said expanded part and including a depending extension spaced from the restricted part and disposed within close proximity to the outer rim of said dial and overhanging said re- 45 duced part to prevent rotation of said member with respect to said dial, and key operative means to permit or prevent removal of said reduced part from said opening.

SAMUEL SEGAL. 50
